MEAT CHOPPER

Donald D. Mallory, Toledo, Ohio, assignor to Toledo Scale Company, Toledo, Ohio, a corporation of New Jersey

Application December 8, 1949, Serial No. 131,753

1 Claim. (Cl. 146—182)

1

This invention relates to a machine for comminuting food and more particularly to a machine of the type known in the trade as a meat chopper and which has an inclined feeding barrel.

Conventional meat choppers are provided with a generally tubular barrel in which rotates a feeding worm and into which opens an ingress neck through which the butcher or other operator feeds the meat or food to be comminuted. At one end of the barrel is located driving machinery for rotating the feeding worm. The other end of the barrel is provided with a perforated plate which extends across the barrel and is usually held in place by a clamping ring or other clamping means removably fitted on the exterior of the barrel. A multiple bladed rotat-

ing knife usually is drivingly engaged in the end of the feeding worm and has blades which are swept over the inner surface of the perforated plate.

Because of the high order of cleanliness and the sanitary condition which it is necessary to maintain in establishments handling food, the barrel, feeding worm, plate and knife of a chopper must be readily removable and separable so that they can be sterilized in order to prevent contamination of the food passing through the machine. Because it is necessary to remove the worm for cleaning, it quite usually is provided with a quickly disengageable driving connection often in the form of a socket in the end of the driving shaft which projects into one end of the barrel and a tenon on the end of the worm which is drivingly engaged in the socket. This connection usually is disengageable merely by moving the worm longitudinally so that it can be quickly removed when desired.

In choppers having inclined feeding barrels when the retaining clamp or clamping ring is disengaged and the perforated plate and knife removed in machines constructed according to the teachings of the prior art, gravity caused the worm to fall out of the end of the barrel. It was necessary, therefore, to awkwardly retain the plate, knife and worm in the barrel when the clamping means was removed and, in many instances, fingers of an operator might be severely bruised during the removal operation or pinched between the parts.

It is an object of this invention to provide means for retaining a worm of a food chopper having an inclined barrel within the barrel when the end plate and its retaining means are removed and until such time as the worm is defi-

2

nitely and individually removed from the barrel. To accomplish this objective the machine must be so designed as to also comply with the requirements below. First, the means for retaining the worm must not interfere with its free rotation. Second, the means for retaining the worm must not require any separate disengagement and should not require any particular effort on the part of the operator because in a large sized meat chopper, the worm may weigh a considerable number of pounds and the operator may be required to use caution in handling it at all.

The mode of achieving this object under these limitations will become apparent from the specification which follows and from the drawings, in which

Figure I is a view in perspective of a large size meat chopper which may be equipped with worm retaining means embodying the invention.

Figure II is a greatly enlarged fragmentary vertical sectional view showing a typical feeding barrel and its associated worm, plate, knife and retainer and illustrating a worm equipped with worm retaining means embodying the invention.

Figure III is a still further enlarged fragmentary detailed view of worm retaining means embodying the invention.

A conventional meat chopper having an inclined feeding barrel and of the type for which the instant invention is designed, may comprise a feeding tray 1 mounted in feeding relationship to a neck 2 (see also Figure II), the lower end of which opens into a general cylindrical feeding barrel 3. The feeding barrel 3 in the chopper shown in the drawings is slightly flaring and is provided with internal flutings 4 to assist a worm 5 in feeding the food to be comminuted from the space beneath the lower end of the neck 2 downwardly and forwardly through the barrel 3 and against the inner face of a perforated plate 6.

The perforated plate 6 has a central aperture through which protrudes a shaft 7 of a multiple bladed rotary knife 8 which is drivingly engaged with the lower end of the worm 5 and which serves, therefore, as an outboard bearing for the worm 5. When the worm 5 is rotated the blades of the knife 8 are swept over the inner face of the perforated plate 6 and clip off small nodules of food which are forced into the openings in the plate by the feeding action of the worm 5. The nodules are extruded through the perforations in the plate 6 by following nodules. The plate 6 and the knife 8, which is journaled therein, are retained at the lower end of the barrel 3

by a generally annular retaining ring 9 which is threaded onto the exterior of the barrel 3 and is provided with an annular recess 10 for grasping the plate 6.

The upper end of the worm 5 is turned down into a cylindrical tenon 11 which is journaled in a sleeve bearing 12 mounted in a reduced diameter portion of the barrel 3. The barrel 3 is socketed in the end of a collar 13 which projects slightly through an exterior housing 14 of the machine. The barrel 3 is retained in the collar 13 by the engagement of a transverse shaft 15 in a notch 16 cut in the outer surface of the barrel 3. The shaft 15 has a flatted portion 17 which can be turned into position to clear the exterior of the barrel 3 by a handle 18 (see Figure I) mounted on its end outside of the housing 14.

The uppermost end of the tenon of the worm 5 is squared as indicated by the reference character 19, and is slidably engageable in a squared socket 20 formed in the lowermost end of a drive shaft 21 which extends concentrically toward the uppermost end of the barrel 3 and is driven by power mechanism located within the housing 14, but not shown in the drawings. Thus, by rotating the flatted shaft 15, free of engagement with the notch 16, the barrel 3 containing the worm 5, blade 6, knife 8 and the ring 9 can be removed as a unit from the chopper merely by sliding it downwardly on the axial line of the worm. When it is desired to disassemble the mechanism to facilitate cleaning or to change the perforated plate 6 to provide a plate having holes of a different diameter as, for example, when changing from the production of hamburger to chili meat, the ring 9 is unthreaded, freeing the plate 6 and knife 8, and thus the worm 5 so that by moving the worm 5 axially it can be withdrawn from driving engagement with the socket 20 and slid downwardly out of the barrel 3.

Indeed, in prior art machines of this general type, whenever the ring 9 was unthreaded and the plate 6 and knife 8 removed, the worm 5 would at once slide downwardly and outwardly frequently falling to the floor where it might be damaged or where it might damage other equipment or fingers or toes of the operator. However, in a meat chopper embodying the invention the accidental displacement of the worm 5 is obviated by mechanism simple in construction and yet effective in action and that does not interfere with rotation of the worm, the removal of the entire barrel and its contents or the removal of the worm 5 from the barrel. This mechanism consists in an annular groove 22 (see also Figure III) which is cut in the inner surface of the sleeve bearing 12 and a resilient snap ring 23 which is emplaced within the annular groove 22 and closely circumjacent the cylindrical tenon 11 of the worm 5 which, due to its resiliency, it tightly grasps.

Therefore, when the plate 6 and knife 8 are removed, thereby freeing the lower end of the worm 5, its weight causes the worm 5 to slide downwardly in the barrel 3 but the almost im-

mediate engagement of the ring 23 with the lower wall of the annular groove 22 stops the movement of the ring 23 and, since the ring 23 is selected to be of sufficient strength to perform the operation, the ring 23 by tightly grasping the cylindrical tenon 11 of the worm 5 prevents this heavy worm from sliding out of the barrel. When it is desired, however, to remove the worm the operator may grasp the lower end of the worm 5 and with a sharp tug withdraw it from the embrace of the ring 23. When it is desired to reinsert the worm 5 the operator merely shoves its squared tenon 19 into the lower end of the sleeve bearing 12 and pushes it upwardly. The tenon 19 opens the ring 23 which then slides onto the cylindrical tenon 11, again in tight grasping relationship.

Having described the invention, I claim:

In a machine for comminuting food which has a downwardly inclined feeding barrel, an ingress opening leading into said barrel and a perforated discharge plate across the lower end of said barrel, in combination, a feeding worm rotatably mounted in said barrel for feeding food therethrough and against the inner side of said plate, a rotary knife driven by engagement with said worm and forming a lower end bearing therefor, said knife bearing against the inner surface of said plate for severing food particles, a clamping member on the exterior of said barrel at its lower end for holding said plate thereon, a driving member extending into the upper end of said barrel and having a disengageable driving connection with said worm which is disengaged merely by relative axial movement of said worm, the said driving member having a smooth cylindrical portion, a bearing consisting of a stationary sleeve within which said smooth cylindrical portion is journaled for free rotation, said sleeve having an interior annular groove therein, and a resilient ring lying loosely within said annular groove and frictionally embracing said smooth cylindrical portion whereby said resilient ring revolves with said smooth cylindrical portion freely in said annular groove and yieldingly permits longitudinal movement of said cylindrical portion when said feeding worm is to be withdrawn from said feeding barrel.
